US00D942976S

(12) **United States Design Patent** (10) Patent No.: **US D942,976 S**
(45) Date of Patent: **** Feb. 8, 2022**

(54) **LAPTOP COMPUTER**

(71) Applicant: **Lenovo (Beijing) Co., Ltd.**, Beijing (CN)
(72) Inventor: **Tianfang Yu**, Beijing (CN)
(73) Assignee: **Lenovo (Beijing) Co., Ltd.**, Beijing (CN)

(**) Term: **15 Years**

(21) Appl. No.: **35/509,992**

(22) Filed: **May 29, 2020**

(80) **Hague Agreement Data**

Int. Filing Date: **May 29, 2020**
Int. Reg. No.: **DM/209533**
Int. Reg. Date: **May 29, 2020**
Int. Reg. Pub. Date: **Aug. 7, 2020**

(30) **Foreign Application Priority Data**

Nov. 29, 2019 (CN) 201930666397.1

(51) LOC (13) Cl. **14-02**

(52) U.S. Cl.

USPC **D14/318**

(58) **Field of Classification Search**
